UNITED STATES PATENT OFFICE

107,301

DESIGN FOR A DRESS

Albert Kaplan, New York, N. Y.

Application November 1, 1937, Serial No. 72,551

Term of patent 3½ years

To all whom it may concern:

Be it known that I, Albert Kaplan, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The ornamentation on the front portion of the waist member of the dress and front belt portion of the skirt represents sequins.

I claim:

The ornamental design for a dress, substantially as shown and described.

ALBERT KAPLAN.
